UNITED STATES PATENT OFFICE.

MAX E. CRANDALL, OF KINGFISHER, OKLAHOMA, ASSIGNOR OF ONE-HALF TO MARTIN J. MEIER, OF KINGFISHER, OKLAHOMA.

WINDOW-SCREEN.

1,142,311.

Specification of Letters Patent.

Patented June 8, 1915.

Application filed March 31, 1914. Serial No. 828,546.

To all whom it may concern:

Be it known that I, MAX E. CRANDALL, citizen of the United States, residing at Kingfisher, in the county of Kingfisher and 5 State of Oklahoma, have invented certain new and useful Improvements in Window-Screens, of which the following is a specification.

This invention relates to window screens 10 and has as its object to provide a novel frame structure for such screens, which frame may be readily assembled by any one and readily adjusted to fit any size window within reasonable limits.

15 It is one aim of the invention to so construct the frame that any inexperienced person may readily and accurately fit there-to the sheet of screen material and this without the use of tools.

20 Various types of knock down frames have been devised intended to be placed upon the market and assembled by a purchaser, but all such structures, so far as I am aware, require the use of tools for fitting the sheet 25 of screen material to the frame, after the frame has been set up. Usually the sheet of material is tacked into place, and unless the person fitting the same is experienced, difficulty will be found in properly stretch- 30 ing the sheet of screen material so that the finished screen is liable to appear bulged and distorted. Furthermore, it is necessary, in the use of such frames, that the sheet of screen material be accurately measured and 35 cut or it must be trimmed after it has been tacked to the frame. In either event, waste of material is liable to occur and the opera- 40 tion is bothersome.

The present invention, therefore, has as 45 a further object to provide a screen frame of such construction that in applying the sheet of screen material thereto it may be measured and cut to the width and height of the window opening in which the screen 50 is to be arranged and may be readily assem- 55 bled with the screen frame without further measurements being necessary and without any particular attention being paid to the stretching of the sheet.

50 Another aim of the invention is to provide a screen frame made up of metallic rails and stiles, so formed from sheet metal as

to be rigid in the assembled frame and yet be exceptionally light in weight.

Further the invention has as its object to 55 so construct the stiles and rails of the frame that they may be adjusted as to length and their sections secured in adjusted position without the employment of tools.

In the accompanying drawings: Figure 1 60 is a perspective view of the screen embodying the present invention. Fig. 2 is a vertical transverse sectional view through one corner of the screen. Fig. 3 is a similar section on the line 3—3 of Fig. 2. Fig. 4 65 is a sectional view, illustrating the manner in which the rails and stiles of the screen frame are to be manipulated in applying the sheet of screen material thereto. Fig. 5 70 is a vertical sectional view through the completed screen. Fig. 6 is a view in elevation of the completed screen. Fig. 7 is a group perspective view, illustrating one of the rails and one of the stiles in position to be assembled. Fig. 8 is a perspective view of one of 75 the locking strips for securing the sections of the stiles and rails at adjustment.

Corresponding and like parts are referred to in the following description and indicated in all the views of the accompanying drawings by the same reference characters.

Except at their ends the stiles and rails of the screen frame are of counterpart construction, and each stile and each rail comprises two telescopically fitted sections which 85 adapt the frame for adjustment as regards its width and height. Each section of each stile and each rail is formed from a sheet metal blank so formed as to be substantially rectangular in cross section. The stiles are 90 indicated in general by the reference character A and the rails by the reference character B, one section of each stile being indicated by the numeral 1 and the other section by the numeral 2, and one section of each rail being indicated at 3 and the other section at 4. As stated, each section is formed from a sheet metal blank and the blank is so folded as to provide spaced side portions 5 and 6 and spaced edge portions 7 and 8. 100 The side portion 5 and edge portion 7 are integrally connected by a fold in the blank as also the side portion 6 and edge portion 7 and the side portion 5 and edge portion 8.

The edge portion 8 is provided with a flange 9 which projects inwardly at right angles therefrom and is overlapped by the free edge of the side portion 6 although spaced therefrom. The said side portion 6 is folded back upon itself to form a flange 10 which is spaced from the face of the said portion and which has its free edge presented in the direction of the edge portion 7. As stated, 10 the sections of each stile and each rail are telescopically fitted together and, consequently, the cross sectional dimensions of the said sections differ to such extent as to permit of such fitting.

15 When the sections are fitted together, the flange 9 of the section of smaller dimensions, which would be the section 1 in the instance of each stile and the section 3 in the instance of each rail, will be overlapped 20 by the flange 9 of the other section 2 or 4, as the case may be, and the free edge portion and flange 10 of the side portion 6 of each of the sections 2 and 4 will be received within the space between the said portion 25 6 and flange 10 of each respective section 1 and 3. For a purpose to be presently explained, each flange 10 is of a width equal to one-half the width of the section of which it forms a part. The portions 6 of 30 the sections of each stile are cut away, as indicated at 11, at the remote ends of the stile, as are also the edge portions 8 and flanges 9, sufficient material being left, however, to permit of the edges of the portions 35 5 and 7 being overturned, as indicated at 12 and 13 respectively so that no sharp edges will be presented. In a like manner the flanges 10 of the sections of each rail are 40 cut away, as indicated at 14, at the remote ends of the said sections. The portions 5 of the sections of each stile are provided at the remote ends of the sections with bolt 45 openings 15, as are also the portions 5 and 6 of the sections of each rail, the latter openings being indicated by the numeral 16.

In assembling the stiles and rails, the remote ends of the sections of each rail are disposed within the cut away ends of 50 the sections of the stiles and bolts, or other suitable securing elements 17, are fitted through the openings 15 and 16 and are provided with nuts 18' which may be tightened for the purpose of securing the assembled ends of the stiles and rails to each 55 other. The bolts are not fitted into place, however, until after the stiles and rails have been connected with the sheet of screen material, as will be presently explained. The sheet of screen material is indicated by 60 the numeral 18 and in cutting this sheet from the roll it is measured and cut in the same dimensions as the window opening in which the screen is to be placed. It is desirable that each corner of the sheet be cut 65 out, as indicated at 19, by lines of incisions

at right angles to each other, so as to permit of the edge portions of the sheet being smoothly fitted to the flanges 10. In fitting the sheet one side edge portion thereof is fitted within the fold forming the flange 10 70 of the sections of one of the stiles or rails, and this member of the frame is turned from the full line position shown in Fig. 4 to the dotted line position shown therein, and this turning movement is continued until 75 the frame member has assumed a position the reverse of its full line position, as illustrated at the top of the said Fig. 4. In thus rotating the member, the edge portion of the sheet of screen material is folded upon 80 itself over the edge of the flange 10, in the manner shown at the bottom of the said Fig. 4. In a like manner the other stiles and rails are assembled with the respective edge portions of the sheet 18, whereupon 85 the screen will be complete except for the application of securing bolts 17 and a locking means provided for holding the telescopic sections of the stiles and rails at adjustment.

90 The locking means, mentioned above, is in the nature of a strip 20 of sheet metal, which is initially bent upon itself at one end, as indicated at 21, this end being hooked over the end edge of the inner section 95 of the stile or rail, as the case may be, with the body portion of the strip extending beside the outer face of the portion 5 of the said section. The sections are then telescopically fitted one into the other and after 100 having been adjusted the projecting ends of the several strips 20 are bent back, as indicated by the numeral 22, so as to engage over the inner end edges of the portions 5 of the respective sections.

105 It will now be understood, and particularly by reference to Fig. 3 of the drawings, that the locking strips 20 serve to prevent the sections of the stiles and rails being further slid into each other after adjustment, and it will be understood, of course, that the sheet of screen material 18 serves 110 to prevent the sections of the stiles and rails being separated or extended. It will, of course, be understood that it is not absolutely essential that the stiles and rails be formed in sections telescopically fitted, for they might be formed in sections adjustably connected in some other manner, or they might be formed integral throughout. Nevertheless, the construction of the sections 115 adapting them to be telescopically adjustably fitted constitutes an important feature of the invention as does also the provision of the flange 10.

120 Having thus described the invention, what is claimed as new is:

1. A window screen frame having its members composed of telescopically connected sections, each section being formed from a 130

sheet blank formed to provide spaced side portions and edge portions integrally connected except between one of the side portions and one of the edge portions, the said side portion of each section being provided at its free edge with a flange for the connection of the edge of a screen sheet.

5 2. As a new article of manufacture, a window screen frame member formed from a sheet blank bent to substantially hollow rectangular form and having one side provided with a flange overlapped by the edge portion of an adjacent side, the said edge portion of the said adjacent side being provided with a flange lying in spaced relation with respect to the said side and adapted for the engagement therewith of an edge portion of a sheet of screen material.

10 3. As a new article of manufacture, a window screen frame member comprising telescopically fitted sections, each formed from a sheet blank bent to substantially hollow rectangular form, one side of each section being provided with a flange overlapped by the edge portion of an adjacent side of the section, the said adjacent side being provided with a flange lying in spaced relation with respect thereto, the said sections in their assembled relation being arranged with the said edge portion and the flange of the said adjacent side of one sec-

tion received between the said adjacent side and the flange of the other section and telescopically.

15 4. A window screen frame comprising separably connected stile and rail members, each of the members being formed from a sheet blank bent to substantially hollow rectangular form, one of said members having two of its adjacent walls cut away at its ends, and the members associated therewith each having one end disposed within the cut away portion of the first-mentioned member, securing elements fitted through the assembled ends of the members, and means upon the members for the connection of a sheet of screen material.

20 5. In a window screen, a frame comprising stiles and rails consisting of telescopically connected sections, and means for holding the sections of each stile and each rail at adjustment comprising a strip bent at one end to engage the interfitted end of one section and at its other end bent to engage with the corresponding end of the other sec-

25 30 In testimony whereof I affix my signature in presence of two witnesses.
